UNITED STATES PATENT OFFICE.

EDWARD A. JOHNSTON, OF CHICAGO, ILLINOIS, ASSIGNOR, BY MESNE ASSIGNMENTS,
TO INTERNATIONAL HARVESTER CORPORATION, A CORPORATION OF NEW JERSEY.

CARBURETER.

1,221,183.

Specification of Letters Patent.

Patented Apr. 3, 1917.

Application filed January 4, 1913. Serial No. 740,108.

To all whom it may concern:

Be it known that I, EDWARD A. JOHNSTON, a citizen of the United States, residing at Chicago, in the county of Cook and State of Illinois, have invented certain new and useful Improvements in Carbureters, of which the following is a full, clear, and exact specification.

This invention relates to carbureters for internal combustion engines.

In the operation of internal combustion engines which use various kinds of oils for fuel, much attention, of necessity, must be given to the proportioning of the different ingredients which, when properly mixed form an explosive mixture. When gasoline and some other comparatively light hydrocarbon oils are used for fuel, an explosive mixture is formed on which an engine undoubtedly operates satisfactorily. But the high cost of gasoline renders its use in large quantities, for instance in the operation of heavy-duty tractors, almost prohibitive. For this reason, among others, kerosene and some other relatively heavy hydrocarbon oils are now being used for fuel. Although the heavy hydrocarbon fuel oils are comparatively inexpensive, their use being favorable from that standpoint, more or less difficulty has been encountered in properly mixing and proportioning the fuel oils with the other constituents to form an explosive mixture to meet all of the requirements for varying load conditions. For instance, when a volume governed internal combustion engine is working on friction or light load, the compression is low, in which case a relatively rich mixture is required for the proper operation of the engine. When the engine is working on a heavy load, the compression is high, therefore, not requiring such a rich mixture, but a greater quantity of relatively lean mixture. It is a well known fact that when heavy fuels are used, the use of water with the mixture is advantageous to prevent pre-ignition and fouling. Under friction or light load conditions no water is required, but under heavy load conditions more or less water must be mixed with the other elements of the explosive mixture, not only to make such mixture more lean, but under said circumstances to prevent pre-ignition and fouling. Even under heavy load, especially overload, conditions too much water may be supplied when the water, oil and air are

supplied at a constant ratio. From the above, it is evident that at times a water supply is necessary, and that at other times detrimental. A problem is thus presented as to when water should be supplied to the mixture of the fuel oil and air; when it should not be supplied to such mixture, and when supplied, in what proportion relative to the other ingredients should it be supplied.

It is therefore the object of my present invention to provide for the supplying of the different ingredients of an explosive mixture in the proper proportions under all and varying operating conditions, so that an engine may operate at all times at the highest efficiency under any particular conditions.

This object is accomplished by providing an improved carbureter, having a plurality of passageways, one for fuel and air, and another for water and air, and suitable valves in said passageways for controlling the supply of fuel, air, and water to provide for an explosive mixture adapted to meet all the requirements for the successful commercial operation of internal combustion engines.

This invention is illustrated on the accompanying sheets of drawings, in which Figure 1 is a top elevation of my carbureter, parts being in section for the sake of clearness;

Fig. 2 is a side elevation of the same carbureter, the fuel and water receptacles being removed from the body of the carbureter.

Fig. 3 is a sectional view of the same carbureter taken in the plane of line 3-3 of Fig. 2;

Fig. 4 is a detail looking into the carbureter from above, the controlling valves therein being in one extreme position;

Figs. 5 and 6 are respectively front and side elevations of the integrally formed valve members used in this carbureter; and,

Fig. 7 is a sectional view of the oil and water containing receptacles, which are adapted to be secured to the carbureter body proper.

The various novel features of my invention will be apparent from the description and drawings, and will be particularly set forth in the appended claims.

My improved carbureter 10 is adapted to be secured to the end head 11 of a cylinder of an internal combustion engine. This carbureter 10, includes a casting or member 12 having a passageway 13 through

which fuel and air are adapted to flow, and a passageway 14 through which water and air are adapted to flow, said passageways 13 and 14 being formed by a partition 15 within the mixing chamber 12. These passageways 13 and 14 terminate in a single passageway or mixing chamber 16, where the fuel, air, and water mix preparatory to passing into the combustion chamber of the engine. Located in the passageway 13 is a removable choke ring 13^a, choke rings of various sizes being necessary where the engine is to be operated in various altitudes. The casting 12 has a lateral extension 17 having an opening 18 registering with the passageway 13 of the casting. In like manner, this mixer has a laterally extending projection 19 having an opening 20 registering with the other passageway 14 of the carbureter. Adapted to be inserted in the opening 18 of the extension 17 and secured therein by a set screw 21 is a removable fuel containing receptacle 22 having an inlet pipe 23 and an overflow 24, by means of which the fuel pressure is maintained constant, said overflow having an outlet pipe 25. This fuel containing receptacle is provided with a baffle plate 26 to prevent fuel from spouting upwardly and out through the receptacle 22 when the cover 27 thereof is removed therefrom. This receptacle is also provided with a passageway 28 registering with an opening 29 in a nozzle 30. This nozzle is provided with a manually operated needle valve 31. In like manner, a water containing receptacle 32 is secured within the laterally extending portion 19, and is provided with a manually controlled needle valve 33, said water containing receptacle having an inlet 34 and overflow outlet 35.

In the side walls of the carbureter are circular openings 36 and 37. Adapted to be inserted in these openings are side caps 38 having extensions 39 adapted to fit within the circular openings 36 and 37. These caps are adapted to be secured to the body of the carbureter by threaded members 40. Each of these caps 38 is provided with a central opening 41 which form bearings for the trunnions 42 of integrally formed valves 43 and 44, the valve 43 being adapted to control the flow of fuel and air through the passageway 13 and the valve 44 being adapted to control the flow of water and air through the passageway 14. Interposed between the valves 43 and 44 and formed integrally therewith is a circular guiding portion 45 which is adapted to reciprocate in a bearing 46 formed in the partition 15. Mounted on and secured to one of the trunnions 42 is a finger member 60 which is loosely mounted upon an adjacent shaft 61 and engages with a projecting portion 62 of a collar member 63. Surrounding this same trunnion 42 and en-

gaging the finger member 60 is a spring or resilient member 47 which tends to open the valves 43 and 44 against the action of the engine speed governor which is operatively connected to the shaft 61, the governor tending to move said valves toward closed position.

The valve member 43 is in the form of a straight plate and is limited in its reciprocatory movements by inwardly extending lugs 50 and 51 associated with one of the end caps 38. The other valve or water controlling valve 44 is provided with a curved portion 51^a which is adapted to cut off and on the supply of water gradually. This valve is also provided with a projection or lip portion 52, which is adapted to project into the passageway 14 to reduce the effective cross sectional area of said passageway after the engine has passed through full load operating conditions and is operating on an overload.

In the operation of internal combustion engines, when the engine is working on friction or light loads, the water controlling valve 44 completely closes the passageway 14, and the valve 43 is in one of its extreme positions but does not quite close the fuel passageway 13. These valves 43 and 44 are held in this one extreme position and prevented from rotating farther in one direction by the projection 51. In these positions of the simultaneously actuated valves 43 and 44, air which is drawn down through the passageway 13, caused by the suction produced upon the occurrence of the inhalation stroke of the piston of the engine, draws with it, upon passing the fuel nozzle 30, a charge of fuel which is mixed with the air in the passageway 16, where it is vaporized, or at least partially so, preparatory to passing into the combustion chamber of the engine, where it is compressed, ignited, and thereby expanded for doing work. When operating on friction or light loads, only a limited amount of fuel and air are drawn into the combustion chamber, and the compression is low. For this reason it is necessary that the fuel charge be comparatively rich in quality. As the load on the engine increases, the speed of the engine tending therefore to decrease, the action of the speed governor causes the valves 43 and 44 to move in a manner so that the fuel controlling valve 43 opens to a greater extent permitting a greater flow of air and fuel, and at the same time the water and air controlling valve 44 is gradually opened, permitting a flow of water and air which mix with the fuel charge, said ingredients mixing in the passageway 16, and thereafter passing into the combustion chamber. As the load on the engine continues to increase, the controlling valves 43 and 44 continue to open in a certain ratio with respect to each other to per-

mit a proportionate amount of fuel and air to pass down through passageway 13 with respect to the water and air which are permitted to pass down through passageway 14 5 of the mixer. From the time when the engine is operating at about twenty-five per cent. of its rated power up to the time it is operating at full power, the valves 43 and 44 are actuated and so related with respect 10 to each other to permit a proportionate amount of fuel and air to flow through passageway 13 and water and air through passageway 14. But if the engine should be overloaded, it has been found by experiment 15 that a greater quantity of fuel is required for the same quantity of water that was being used by the engine when operating at full load. In view of this fact, it is necessary that the effective cross-sectional area of 20 the fuel passageway 13 be increased by actuating the valve 43 in the same direction, while at the same time the simultaneously actuated water controlling valve 44 is to maintain the water and air supply through 25 its passageway 14 in the proper proportion. In order to accomplish this result, the water controlling valve 44 has been provided with the lip portion or projection 52 which projects into the passageway 14 from the time 30 the engine starts to operate on an overload and remains in said passageway until the engine load is decreased to its normal rated full load capacity. The effect of the lip or projecting member 52 of valve 44 projecting 35 into the passageway 14 is to maintain the effective cross-sectional area of the passageway 14 at the proper value, thereby maintaining the air supply therethrough at the proper value, while at the same time the 40 effective cross-sectional area of the fuel passageway 13 is increased, permitting a greater flow of air therethrough and thereby a greater flow of fuel. It is, therefore, seen that when the engine is operating upon friction or light loads, the fuel controlling valve 45 is slightly open to permit a flow of fuel for supplying a relatively rich mixture up to the point where the engine operates at about twenty-five per cent. of its rated power; 50 that from there on up to full load, the fuel controlling valve 43 and water controlling valve 44, which are simultaneously actuated, bearing a certain or desirable ratio with respect to each other, permit a proportionate supply of fuel and air to pass through the passageway 13 with respect to water and air which pass through the passageway 14; and 55 that when the engine is operating on overloads, said fuel controlling and water controlling valves, although both continue to move in the same direction, cause, due to style of valves, a disproportionate amount of fuel and water to be supplied.

By means of my improved carbureter with 60 its valve arrangement, the engine is adapted

to operate at its highest efficiency under all operating conditions. Furthermore, by providing integrally formed valves, such as herein disclosed, the positioning of said valves being accurately and definitely determined to meet the commercial requirements for successful operation of an engine of a particularly rated power, there is no danger of the valves being readjusted with respect to each other, causing the engine to 70 operate unsatisfactorily, by one inexperienced in the operation and care of gas engines.

There may be various modifications in the precise form and arrangement of my invention as particularly herein shown and described, and it is my intention to cover all such arrangements and modifications which do not involve a departure from the spirit and scope of my invention as set forth in the 80 appended claims.

What I claim as new is:

1. In a carbureter for internal combustion engines, the combination of a member having a plurality of adjacent passageways 90 therein, one for fuel and air and another for water and air, and means within said member for independently controlling the supply of fuel and air through one of said passageways and water and air through the other of said passageways.

2. In a carbureter for internal combustion engines, the combination of a member having a plurality of passageways therein, one for fuel and air and another for water and 100 air, and a valve member within said member for independently controlling the supply of fuel and air through one of said passageways and water and air through the other of said passageways.

3. In a carbureter for internal combustion engines, the combination of a member having a passageway for fuel and air and another passageway for water and air, and a valve member having a plain portion and 110 an irregular portion associated with said passageways for controlling proportionately and disproportionately under different load conditions the supply of fuel, water and air therethrough.

4. In a carbureter for internal combustion engines, the combination of a member having a passageway for fuel and air, and another passageway for water and air, and a valve member having different portions 120 thereof to control proportionately and disproportionately under different load conditions the supply of fuel and air in one of said passageways and water and air in the other passageway.

5. In a carbureter for internal combustion engines, the combination of a member having a plurality of passageways, and simultaneously actuated fluid controlling valves in said passageways, one of said valves in 130

- one position preventing a fluid flow in one of said passageways and another of said valves permitting a fluid flow in another of said passageways, upon a movement of 5 said valves said first mentioned valve permitting a flow of fluid in proportion to an increased flow permitted by said second mentioned valve, and upon a continued movement of said valves, said first mentioned valve permitting substantially the same flow of fluid while said second mentioned valve permits an increased flow of fluid.
6. In a carbureter for internal combustion engines, the combination of a member having a plurality of passageways, and simultaneously actuated fluid controlling valves in said passageways, one of said valves in one stage of engine operation preventing a fluid 10 flow in one of said passageways and another of said valves permitting a flow in another of said passageways, said valves in another stage permitting a proportionate fluid flow in said passageways, and said valves in still 15 another stage causing a disproportionate fluid flow in said passageways.
7. In a carbureter for internal combustion engines, the combination of a member having a plurality of passageways, means for supplying fuel to one of said passageways, means for supplying water to another of said passageways, and simultaneously actuated valves in said passageways for controlling the flow of said fuel and water, said 20 valves during one stage of engine operation preventing a flow of water and permitting a flow of fuel, during another stage permitting a proportionate flow of water and fuel, and still during another stage causing a 25 disproportionate flow of water and fuel.
8. In a carbureter for internal combustion engines, the combination of a member having a plurality of passageways, means for supplying fuel to one of said passageways, means for supplying water to another of said passageways, and simultaneously actuated valves in said passageways for controlling the flow of said fuel and water, said valves during friction or light load 30 operating conditions preventing a flow of water and permitting a flow of fuel, from light to full load operating conditions permitting a proportionate flow of fuel and water, and for overload conditions causing a disproportionate flow of fuel and water.
9. In a carbureter for internal combustion engines, the combination of a member having a plurality of passageways through 35 which ingredients of an explosive mixture are adapted to flow, a valve for controlling the flow through one of said passageways, and a second valve for controlling the flow through another of said passageways, said second valve having a curved portion 40 adapted to cut off and on the flow in one of said passageways gradually, said valve also having another portion adapted to change the effective cross section of said passageway under certain operating conditions.
10. In a carbureter for internal combustion engines, the combination of a member, and a plurality of passageways through which ingredients of an explosive mixture 45 are adapted to flow, a straight valve adapted to control the flow through one of said passageways, and a second valve adapted to control the flow through another of said passageways, said second valve having a curved portion adapted to cut off and on the flow in one of said passageways gradually, said valve also having a projection adapted to reduce the effective cross section of said 50 passageways under certain operating conditions.
11. In a carbureter for internal combustion engines, the combination of a member having a plurality of passageways, means for supplying fuel to one of said passageways, means for supplying water to another of said passageways, and means having plain and irregular portions for automatically controlling the flow of fuel and water in a manner to prevent a flow of water and 55 permit a flow of fuel at one stage of engine operation, to permit a proportionate flow of water and fuel during another stage, and to cause a disproportionate flow of water and fuel during another stage.
12. In a carbureter for internal combustion engines, the combination of a member having a plurality of passageways, means for supplying fuel to one of said passageways, means for supplying water to another of said passageways, and means having plain and irregular portions for automatically controlling the flow of fuel and water in a manner to prevent a flow of water and 60 permit a flow of fuel during friction or light load operating conditions, to permit a proportional flow of fuel and water from light to full load operating conditions, and to cause a disproportionate flow of fuel and water for overload conditions.
